UNITED STATES PATENT OFFICE.

LINCOLN C. STOCKTON AND CHARLES F. GODDARD, OF DENVER, COLORADO, ASSIGNEES,
BY DIRECT AND MESNE ASSIGNMENTS, TO THE METAL SEPARATION COMPANY, OF
DENVER, COLORADO, A CORPORATION OF COLORADO.

APPARATUS FOR SAVING METALLIC VALUES.

1,327,885.

Specification of Letters Patent. Patented Jan. 13, 1920.

Application filed March 18, 1918. Serial No. 223,014.

To all whom it may concern:

Be it known that we, LINCOLN C. STOCKTON and CHARLES F. GODDARD, citizens of the United States, residing at the city and county of Denver and State of Colorado, have invented certain new and useful Improvements in Apparatus for Saving Metallic Values; and we do declare the following to be a full, clear, and exact description 10 of the invention, such as will enable others skilled in the art to which it appertains to make and use the same, reference being had to the accompanying drawings, and to the characters of reference marked thereon, 15 which form a part of this specification.

Our invention relates to apparatus for separating metallic values from pulp in which these values are contained either in a free state or otherwise.

20 The specific apparatus illustrated in the drawing consists of a sluice divided longitudinally into channels by spaced partitions, the bottom of the sluice being provided with a number of transversely arranged openings 25 which are properly spaced, there being a receptacle or container, preferably removable, into which the precipitated values which pass through the respective openings pass.

Each of these openings may be provided 30 with a series of transversely arranged parallel wires, the said wires being unequally spaced in the various openings, those in the opening nearest the head or upper extremity of the sluice being the farthest apart, 35 while the wires or metallic ribbons in the other openings increase in number, whereby the spaces between them gradually diminish toward the lower extremity or tail of the sluice, provision being made for diminishing 40 the volume and pressure of the water which is delivered to the containers and which constitutes the rising currents in order to classify the values which are separated from the pulp.

45 Having briefly outlined our improvement we will proceed to describe the same in detail, reference being made to the accompanying drawing in which is illustrated one form of apparatus for practising the invention.

50 In this drawing:

Figure 1 is an end elevation of our improved sluice being a view looking toward the lower extremity of the sluice or in the direction of arrows 1, Fig. 2.

Fig. 2 is a side elevation of the apparatus 55 or a view looking in the direction of arrows 2, Fig. 1.

Fig. 3 is a top plan view of the apparatus, or a view looking in the direction of the arrows 3, Fig. 2.

Fig. 4 is a section taken through the wash water conduit of the sluice cutting the same where a valve for controlling the passage of water from the conduit into a container is located, the section being taken on the line 65 adjacent the point of arrow 4, Fig. 2, the parts being shown on a greatly enlarged scale.

Fig. 5 is a top plan view of one of the cross wire holders which are set into the 70 openings in the bottom of the sluice, the same being shown on a larger scale than in Figs. 1, 2 and 3.

Fig. 6 is a fragmentary longitudinal section of the sluice taken on the line 6—6, Fig. 75 3, the parts being shown on a much larger scale.

Fig. 7 is a section taken on the line 7—7, Fig. 5 viewed in the direction of the arrows.

Fig. 8 is a perspective view of one of the 80 receptacles or containers for the metallic values which are precipitated through the openings in the bottom of the sluice.

Fig. 9 is a fragmentary perspective view of the bottom of the sluice illustrating the 85 distributing means for the wash water, arranged at the top of each container.

The same reference characters indicate the same parts in all the views.

Let the numeral 5 designate a sluice considered in its entirety and including a top member 6 which constitutes a sluice proper, the same being composed of a bottom 7 having transverse openings 8 formed therein at suitable intervals, each of said openings being provided with a device 9 carrying a series of wires 10 which are arranged in parallel relation across each opening 8 and held in place by end pieces 12 whose upper edges are engaged by the extremities of the wires 10, these extremities being also bent downwardly as shown at 13 and clamped between the end pieces 12 and other pieces 14 which are arranged outside of the pieces 12, the downwardly bent extremities of the wires being clamped between the pieces 12 and 14 by means of rods 15 and fastening nuts 16. The end pieces 12 are spaced by parallel side

parts 17 whose extremities are mortised into the pieces 12, as shown at 18. This construction is illustrated in Fig. 5 and simply consists of a series of wires 10 which are arranged transversely across the bottom of the sluice, the other features just described being employed for maintaining the wires in place. In other words, the frame work is simply a holder for the series of parallel wires 10 which are unequally spaced in the different openings, whereby the metallic values are classified in the various receptacles or containers 58 which are arranged below these openings. Each container is normally open 15 at the top and its upper extremity is forced tightly against a sheet of packing material 19 which is applied to the under surface of the sluice above each container and having openings 20 to register approximately with 20 the openings 8 formed in the bottom of the sluice. The wire structure illustrated in Fig. 5 is applied to the bottom of the sluice so that the opening therein across which the wires 10 are stretched registers with the 25 opening 8 in the bottom of the sluice, the wire holding structure being held in place in any suitable manner, as by means of screws 21 which are passed through openings in the bottom of the sluice and threaded into 30 pieces 14 of the wire holding structure. Secured to the sluice below each sheet of packing material is a rectangular frame 22 containing two parallel troughs 23 arranged transversely of the sluice and connected at 35 one extremity by a trough member 24. This frame work is secured to the bottom of the sluice in any suitable manner, as by means of bolts 25 which are passed through openings 26 formed in flanges 27 of the structure. 40 The troughs 23 are perforated, as shown at 28, to receive wash water which is supplied from a conduit 29 extending longitudinally of the sluice and at one side thereof. The bottom of the conduit 29 is provided with a 45 perforation 30 arranged directly above the end trough member 24 of the frame 22. The water which is supplied to each container 58 passes through one of these openings 30 and the volume of water may be regulated at will 50 by adjusting a valve 31 whose stem 32 passes through a threaded opening 34 formed in the top of the conduit, the upper extremity of the stem having a hand wheel 35 for convenience of manipulation. 55 The containers 58 are supported below the sluice proper by means of a floor 36, the bottom of each container being provided with bearings 37 in which is journaled a shaft 38 having a crank 39 and a roller 40, whereby 60 as the shaft is given a partial rotation, the roller 40 is brought into engagement with the floor 36 and the top of the tank forced tightly upwardly against the corresponding packing sheet 19. Each shaft 38 65 has a crank handle 41 at one extremity there-

of, the same being equipped to coöperate with a segmental ratchet 42, whereby the shaft 38 may be locked in the desired position of adjustment. Each of these containers has its bottom provided with a number 70 of rollers or casters 43, whereby when the shaft 38 is adjusted to release any container, the latter may be drawn from underneath the sluice in order that its metallic contents may be removed. To facilitate the handling 75 of the containers each is provided at one end with a hand piece 44.

The bottom 7 of the sluice is provided with a number of longitudinally disposed partitions 45 which are suitably spaced, 80 whereby the sluice is divided into a number of longitudinally disposed compartments or channels 46, thus maintaining an approximately even distribution of the pulp or water, carrying the material under treatment 85 over the bottom of the sluice and preventing any tendency of the sluice current to flow otherwise than in a direct course. It is, of course, advisable in a structure of this kind that the pulp under treatment 90 should be evenly distributed over the bottom of the sluice and that the volume of the flowing sluice should be of even depth or thickness on the sluice bottom in order that the rising currents of wash water from the 95 container may properly act thereon in the separation of the metallic values which are precipitated through the wire covered openings into the containers, as heretofore described.

The sluice may be mounted in any suitable manner which will permit adjustment for the purpose of increasing or diminishing the flow of pulp through the sluice. As illustrated in the drawing the bottom 36 of the 105 structure on which the containers rest is supported by longitudinally disposed beams 47 which are in turn supported by transverse beams 48, the latter being supported by adjustable screws 49 which are threaded 110 in bottom parts 50, the screws being adjustable in any suitable manner. The sluice proper is supported by uprights 51 whose upper extremities engage channel members 52 which directly engage the under surface 115 of the bottom of the sluice, the uprights being secured to the sluice by suitable fastening devices 53. The lower extremities of these uprights rest upon the floor 36 of the structure.

From the foregoing description, the use and operation of our improved apparatus as well as the manner of practising the process covered by this application, will be readily understood.

Assuming that the parts of the apparatus are assembled, as illustrated in Figs. 1 and 2 of the drawing, the wash water will be fed into the conduit 29 until the tanks or containers 18 are full. The pulp to be treated 130

will then be turned into the sluice and the wash water being simultaneously supplied will cause currents of water to pass upwardly from the containers through the 5 openings in the bottom of the sluice and through the wires 10 with which these openings are provided, these rising currents of water serving to sustain the gangue while they allow the heavier metallic values to 10 precipitate or pass downwardly into the containers. By virtue of the construction and arrangement heretofore described the volume and pressure of the water delivered to each container may be controlled by adjusting the valves 31 and through the medium of these valves the pressure and volume of water as it rises through the openings in the bottom of the sluice will be proportioned according to the material to be 15 sayed or precipitated in the several containers. For instance, the uppermost container will receive the heaviest and largest particles while the particles in the other containers will diminish in weight and size 20 successively from the head to the lower extremity of the sluice.

When it is desired to clean up or remove the values from any container it will only be necessary to loosen the container by adjusting the crank shaft 38, after which the container may be moved laterally from underneath the sluice proper, as heretofore indicated.

Having thus described our invention, 35 what we claim is:—

1. Concentrating apparatus, comprising a sluice having an opening in the bottom thereof, a readily removable tank positioned below said opening, means on the under side 40 of said sluice to discharge water into said tank and means to seal said tank against said under side of the sluice.

2. Concentrating apparatus, comprising a sluice having an opening in the bottom 45 thereof, a readily removable tank positioned below said opening, means on the under side of said sluice to discharge water into said tank, and means to seal said tank against said under side of the sluice, said means including packing material disposed between the sluice and the edges of the tank.

3. Concentrating apparatus, comprising a sluice having an opening in the bottom thereof, a readily removable tank positioned

below said opening, and means to clamp 55 said tank securely against said sluice, and means on the under side of the sluice to discharge water into the tank.

4. Concentrating apparatus, comprising a sluice having an opening in the bottom 60 thereof, a readily removable tank positioned below said opening, means to clamp said tank securely against said sluice, means on the under side of the sluice to discharge water into the tank, and a runway below 65 said sluice on which said tank is mounted.

5. Concentrating apparatus, comprising a sluice having an opening in the bottom thereof, a readily removable tank positioned below said opening, means to clamp 70 said tank securely against said sluice, means on the under side of the sluice to discharge water into the tank, and a runway below said sluice on which said tank is mounted, said tank being provided with wheels. 75

6. The combination of a sluice proper whose bottom is provided with openings, packing material applied to the lower surface of the bottom of the sluice adjacent the respective openings, containers readily 80 movable respectively arranged underneath the sluice and in communication with the respective openings, means for forcing the containers upwardly into engagement with the respective layers of packing material 85 and securing and sealing the containers in place, and means for introducing liquid in measured volume into the respective containers.

7. The combination of a sluice proper 90 whose bottom is provided with open areas, packing material applied to the lower surface of the bottom of the sluice adjacent the respective open areas, removable containers 95 respectively arranged underneath the sluice and in communication with the respective open areas, and means for releasably applying the containers to the sluice below the bottom thereof to seal them there against, the containers being arranged to be respectively in communication with the said open areas of the sluice, and means for introducing liquid in measured volume into the respective containers. 100

In testimony whereof we affix our signatures.

LINCOLN C. STOCKTON.
CHARLES F. GODDARD.

It is hereby certified that the assignee in Letters Patent No. 1,327,885, granted January 13, 1920, upon the application of Lincoln C. Stockton and Charles F. Goddard, of Denver, Colorado, for an improvement in "Apparatus for Saving Metallic Values," was erroneously described and specified as "The Metal Separation Company, of Denver, Colorado, a Corporation of Colorado," whereas said assignee should have been described and specified as *The Metals Separation Company, of Denver, Colorado, a Corporation of Colorado*, as shown by the records of assignments in this office; and that the said Letters Patent should be read with this correction therein that the same may conform to the record of the case in the Patent Office.

Signed and sealed this 10th day of February, A. D., 1920.

[SEAL.]

M. H. COULSTON,
Acting Commissioner of Patents.

Cl. 83—82.
